SWITCH MECHANISM

Charles A. Good, Oakland, Calif.

Application December 29, 1930
Serial No. 505,330

6 Claims. (Cl. 200—50)

This invention relates to switch mechanisms of the type combining cartridge fuses therewith and arranged to be mounted on a wall or control panel for controlling the line current to and the 5 operation of commercial types of electric motors and analogous electrically powered machines, such switch mechanisms being commonly known as line and motor switches.

An object of the invention is to provide a 10 switch mechanism of the character described which will be smaller, more compact, reliable and safe in operation and easier to install and operate than similar mechanisms heretofore employed, owing to a particularly efficacious manner of combining the switch and fuse units and a 15 novel construction and mode of operation of such units.

Another object of the invention is to provide 20 a switch and fuse unit of the character described in which an improved switch construction is advantageously embodied therein to provide for a better contact of the switch contact members with a positive prevention of arcing, a secure holding of said contact members against 25 accidental disengagement, a complete switch operation with a comparatively short and easy movement of an operating member, and a full shielding and housing of all current carrying parts.

30 A further object is to provide a switch mechanism of the character described in which the fuse and switch units are in superimposed or one in front of the other relation with the fuse unit carried by the movable contact carrying 35 block in such manner as to effect a saving in space and material and provide a more compact mechanism as a whole, as well as other advantages hereinbefore noted.

Still another object is to provide a switch 40 mechanism of the character described in which the switch contact members are positively urged into and out of an effective wiping contact by spring means arranged to insure a good contact at all times and a quick circuit breaking operation without arcing.

The invention possesses other objects and features of advantage, some of which, with the foregoing, will be set forth in the following description of the preferred form of the invention 50 which is illustrated in the drawing accompanying and forming part of the specification. It is to be understood, however, that variations in the showing made by the said drawing and description may be adopted within the scope of the 55 invention as set forth in the claims.

Referring to the drawing,

Figure 1 represents a longitudinal sectional view of the switch mechanism of this invention.

Figure 2 represents a top plan view of the switch mechanism with parts broken away and 60 parts shown in top plan.

Figure 3 is a cross sectional view taken on the plane of line 3—3 of Figure 1.

Figure 4 is a fragmentary sectional view similar to Figure 1 but showing the switch as when 65 open.

The present embodiment of this invention, as shown in detail in the drawing, is seen to comprise a rectangular and relatively small base plate 1 preferably formed of insulating or non-conducting material and arranged to support a fixed housing 2 and a slidable housing 3 with the former telescoping the latter. In both housings switch mechanism 9 is arranged, whereas the slidable housing carries a plurality of fuses 70 4 of the cartridge type which are electrically connected with the switch mechanism. The arrangement is such that when the slidable housing is moved in and out of the fixed housing the switch mechanism will be closed and opened. 75 Such movement of the slidable housing is effected by a crank shaft 11 journalled in and between walls 12 of the fixed housing and operated by a crank arm or lever 14 disposed on a side of said fixed housing. Connecting rods 15 are pivoted to the crank shaft as at 16 and to outer sides of the slidable housing as at 17, said rods being on opposite sides of said housing. 80 These parts are arranged so that when the switch is open the crank arm or lever 14 will lie in a horizontal plane on the side of housing 3 and its associated parts will be disposed in such position that the slidable housing is prevented from accidental movement out of its withdrawn position. 85

The fixed housing 2 comprises the side walls 12 extending outward from the base plate 1 at one end of the latter, and a top wall 20 joined to said side walls. The wall 20 is arranged so that its under side is slidably engaged by said slidable housing when the latter is extended between the side walls 12 or, in other words, is telescoped by the fixed housing. While, as here shown, the fixed housing is made of independent walls it may be formed as one piece 100 105 and integral with the base 1 if so desired.

Between the walls 12 and on the base 1 is a block 21 arranged to be covered by a cover plate 23, the sides of said plate abutting the side walls 12. The block 21 is provided with parallel 110

grooves or recesses 25 in which contact members 26 are fixed. In the present instance three of such contacts are employed since the present unit is for three phase circuits but it is obvious that any number of contacts may be used. The contacts 26 are elongated and at their outer ends carry binding posts 27 accessible from above the block 21 upon removal of the cover plate 23. The inner ends of said contacts are counter sunk in hump like portions 28 of said block, and are exposed for engagement with movable contacts 29 of the switch mechanism. The free ends of contacts 26 and 29 are bent laterally or humped as at 30 and 31 respectively, in such manner that an interlocking engagement thereof will take place to prevent accidental disengagement thereof. The sides 32 of the humps 28 are inclined or curved forward and outward away from the ends of contacts 26 so that when the contacts are moved apart the contacts 29 will be quickly spaced clear of contacts 26 to prevent arcing. Furthermore these surfaces or sides 32 act as guides for the ends 31 of contacts 29 when the latter are moved towards contacts 26.

The slideable housing 3 is generally rectangular and formed to define an outer compartment 34 and an inner compartment 35. In the outer compartment are fuse sockets or clips 36 for the three cartridge fuses 4, these parts being covered by a removable or suitably openable lid or cover plate 37 which, it is noted, lies under the outer wall of the fixed housing 2 and cannot be opened when the switch is closed but is openable when the switch is open.

On the base plate 1 are binding posts 38 which are connected by flexible or pig tail conductors 39 with certain of the fuse clips 36. The other fuse clips have pig tail connections 40 with the movable contacts 29. These contacts, it will be noted, are arranged in the lower or inner compartment 35 of the housing 3 which compartment is suitably partitioned and recessed to separately accommodate and protect the two sets of pig tail connections aforesaid, as well as said contacts 29.

The contacts 29 are in the form of elongated bars and at their inner ends are pivotally held in recesses 42 whereas the outer ends 31 are disposed well in front of the slideable housing and are capable of lateral movement to ride over humps 28 and into and out of engagement with contacts 25. Bowed springs 43 are fixed at certain ends to the inner ends of said contacts 29 and at their other ends slidably bear upon the contacts 29 in such manner as to urge said contacts outwardly towards contacts 25. Owing to these springs, the contacts 29 are caused to positively engage with and be securely held engaged against the contacts 26, as well as to be moved with a quick snap action clear of contacts 25 when slidably withdrawn therefrom. These contacts 29, although projected from housing 3, are however shielded by the housing when withdrawn from contacts 26 since they lie in part in both of housings 2 and 3 when so withdrawn.

It will now be seen that the switch mechanism is in part housed by housing 2 and in part by housing 3, both of which housings fully shield the switch parts to prevent accidental contact therewith by the operator of the switch. This makes for a compact small switch unit which will take up comparatively little room and may be easily installed. By having the fuse unit combined with the housing 3 and taking up no more room than the housing itself, except for a slightly increased depth or thickness of the housing,

greater space economy is provided and a saving in material and parts is also effected. Also the unit is made comparatively flat on its exposed or outer side with no current carrying parts exposed

With reference to the foregoing description and accompanying drawing, it will be apparent that the switch mechanism of this invention will provide the advantages and objects hereinbefore noted in a particularly efficient manner.

I claim:

1. In switch mechanism, a base plate, a fixed housing on said plate, a movable housing on said plate, switch contacts carried and shielded by said housings and arranged to be engaged and disengaged upon movement of said movable housing, a guideway in said fixed housing arranged to engage and deflect the contact on said movable housing upon movement of said housing and fuse sockets carried by said movable housing and electrically connected with the switch contacts carried by said movable housing.
2. In switch mechanism, a base plate, a fixed housing on said plate, a movable housing on said plate, switch contacts carried and shielded by said housings and arranged to be engaged and disengaged upon movement of said movable housing, fuse sockets carried by said movable housing and electrically connected with the switch contacts carried by said movable housing, the contacts carried by said movable housing being movable relative thereto, and spring means auxiliary to said last named contacts arranged to urge the last named contacts into engagement with the other contacts.
3. In switch mechanism, a base plate, a fixed contact thereon, another contact movable on the base plate into and out of engagement with the fixed contact, a movable support for said movable contact, a spring disposed between said support and movable contact and resiliently urging said movable contact into engagement with said fixed contact, and a fuse socket mounted on said support and electrically connected with said movable contact.
4. In switch mechanism, a base plate, a fixed housing thereon, another housing slideable on said base plate and within the other housing, switch contacts in the fixed housing, said slideable housing having inner and outer compartments, switch contacts mounted in and extending from the inner compartment into the fixed housing and arranged to be engaged with and disengaged from the other contacts upon sliding movement of said slideable housing, and fuse sockets in the outer compartment electrically connected with the contacts in said inner compartment.
5. In switch mechanism, a base plate, a fixed housing thereon, another housing slideable on said base plate and within the other housing, switch contacts in the fixed housing, said slideable housing having inner and outer compartments, switch contacts mounted in and extending from the inner compartment into the fixed housing and arranged to be engaged with and disengaged from the other contacts upon sliding movement of said slideable housing, fuse sockets in the outer compartment electrically connected with the contacts in said inner compartment.
6. In switch mechanism, a base plate, a fixed housing thereon, another housing slideable on said base plate and within the other housing, switch contacts in the fixed housing, said slideable hous-

ing having inner and outer compartments, switch contacts mounted in and extending from the inner compartment into the fixed housing and arranged to be engaged with and disengaged from the other contacts upon sliding movement of said slidable housing, fuse sockets in the outer compartment electrically connected with the

contacts in said inner compartment, and a removable cover for the outer compartment arranged to be held against removal by said fixed housing when the switch contacts are engaged with one another.
